UNITED STATES PATENT OFFICE

GEORGE MORRISON, OF POUGHKEEPSIE, NEW YORK

VENDING MACHINE

Application filed August 14, 1930. Serial No. 475,169.

This invention relates to a vending machine for dispensing articles, one at a time and is controlled by novel mechanism which is released by the insertion of the proper coin 5 which allows one article to be ejected for each coin inserted.

The object of the invention is to provide a novel brake or cushion whereby the conveyor on which is mounted the supports for 10 the articles to be vended, is prevented from a too fast movement after being released.

Another object is to provide a simple, durable and efficient machine for the purpose intended.

15 With these and other objects in view, my invention consists in certain novel construction and combination of parts as will hereinafter be fully described and claimed and illustrated in the accompanying drawings, in 20 which like figures of reference refer to corresponding parts in all of the views, but it is understood that slight changes may be made without departing from the spirit of the invention.

25 In the drawings:—

Figure 1 is a partial side elevation of the device, shown with the outer casing removed to expose the working parts.

30 Figure 2 is a partial top plan view partly in section of the locking mechanism.

Figure 3 is a similar view, but showing the parts in another position, taken on the line A—A of Figure 1.

35 Figure 4 is a partial top plan view of the operating mechanism, showing the carriers.

Figure 5 is an enlarged detail partial view of the brake or cushion device.

40 Figure 6 is a partial detail view, showing the method of operating the device with a number of coins.

Figure 7 is a partial detail view of the coin operated mechanism, showing the same in a released position and also the coin box.

45 Figure 8 shows another view of the same, showing the method of stacking the coins.

Figure 9 is a partial front view of the machine with the casing removed.

Referring to the drawings:—

50 No outer casing is illustrated or described,

as this is a matter of detail not involved in the invention, and which will have to be adapted to suit local conditions, and also it may be stated that a number of the machines or units may be mounted together in a single 55 casing if desired.

In the device as here shown, there is provided a mounting plate 10 which may be secured within a casing, and to this plate are secured two vertical uprights 11 by the angle 60 iron 12, and within said uprights are journaled the parallel shafts 13 and 14, on which are secured the sprocket wheels 15 which carry the conveyor chains 16, which at suitable intervals are connected together by the cross 65 bars 17, on which are mounted the article supports 18 which are of angular form, having a short leg 19 adapted to contact with a second cross bar 20 to hold the supports in operative position on the front of the machine, while the added weight of the support will upon the upward travel on the back of the machine fold them as shown to take up less space when not in use. 70

The upper shaft 14 is shouldered at its ends 75 which are threaded and supplied with the nuts 21 so that said shaft 14 may be adjustably mounted in a slot 22 in the uprights 11, for the purpose of taking up the slack of the conveyor.

To one of the uprights 11, near the lower 80 part thereof is secured a plate 23 which carries the operating and lock mechanism.

One end of the shaft 13 is extended through one upright 11 and the plate 23, and has secured thereon by the pin 24 a release wheel or disk 24 which is provided with the two stops 25 on its periphery which are adapted to contact with the two ends 26 which are formed on an escapement lever 27 which is pivoted as at 28 to the plate 23, preventing the rotation of the shaft 13 when said escapement lever 27 is in either of its extreme positions as shown in Figure 1. 85

For operating this escapement lever, there is provided a rod 29 slidably mounted in the bearings 30 secured to the plate 23, and this rod 29 is provided with a pin 31 in contact with the lower end of the escapement lever 27, to move said lever 27 against the action of 90 100

the spring 32 and the rod 29 against the action of the spring 33 secured to a pin 34 in said rod 29.

The forward end of the rod 29 is provided with a collar 35 and a portion 36 which is mounted within a finger plunger 37 containing a spring so that said plunger 37 may first be moved inward for a short distance without contacting with the collar 35 by which it moves the rod 29.

10 A coin controlled lock is provided for this rod, which comprises a coin runway 38 having a coin inserting slot 39; while the rear side of the plunger 37 is cutaway to receive the coin 40 which rests upon a stop 41 secured to the plate 23.

Above the plunger 27 and pivoted to the plate 23 is a latch 42 having a hooked end 43 adapted to engage a notch 44 formed in the rod 29 for locking the same against movement.

Said latch 42 is normally held in a locked position by the spring 45, and is raised to release said rod 29 by the action of the coin 40 which engages with a pin 46 projecting from the rear side of said latch 42, the pin riding up over the coin; the cut-out portion 47 of the plunger 37 pushing the coin 40 against said pin 46 as the plunger is forced inward by the operator; while after the coin 40 has traveled past the stop 41 it will drop from the plunger into a chute which will stack it in the coin box.

The stacking of the coins 40 is accomplished (see Figures 7 and 8) in the following manner.

Below the plate 23 and within the casing is mounted a coin box comprising a box 50 having a chute 51 within which the coin drops from the plunger 37 and runs down an incline 52 striking a stop 53 and falling on its side in a pile in the holder 54; said coin box being closed by a door 55 having a window 56 and a lock 57.

45 Should it be desired to arrange the lock to be operated by a number of coins, this is accomplished by allowing the first coins to pass through the cut-out and stack up against a stop, while the last or upper coin will register with the cut-out portion and act as the wedge to raise the latch.

The article supports 18 may be formed with a number of fingers 58 which as the support descends will pass through a stripper or delivery table 59 mounted in the casing.

55 For preventing the too rapid rotation of the sprockets 15 and a quick descent of the supports 18 I have provided a brake or cushion device, comprising a cylinder 60 closed on its lower end and pivoted to the plate 23 so that it may swing up and down; and this cylinder 60 is provided with a head 61 having a suitable stuffing box through which is reciprocated a stem 62 which has its outer end pivoted to the disk 24 as at 63, while its inner

end is provided with a piston 64 slidably mounted within the cylinder 60 and provided with a small hole 65 through which a liquid such as oil may pass; and it will thus be seen that as the disk 24 rotates, all of the oil in said cylinder 60 will have to pass from one end to the other through the small hole 65 in the piston, thus retarding the quick rotation of said disk 24 and providing a slow movement to the conveyor 16.

75 For preventing the operation of the device through the insertion of small coins, slugs, etc.; the plate 23 right back of the cut-out portion in the plunger is provided with an opening slightly smaller than the required coin, so that all small coins will drop therethrough and not stay in the plunger.

80 Having thus described my invention, what I claim as new and desire to secure by Letters Patent, is—

85 A vending machine comprising a pair of uprights spaced apart in parallel relation, a lower transverse shaft journaled in said uprights near their lower ends, an upper transverse shaft adjustably mounted in said uprights near their upper ends, sprocket wheels mounted upon said shafts, endless conveyors carried by said sprocket wheels, article supports pivoted to said conveyors and adapted to support articles upon them during their downward travel as actuated by the weight of the articles, an escapement wheel secured on the lower shaft, an escapement lever coacting therewith, a cushion device for preventing the too rapid travel of said conveyor, comprising a cylinder pivoted adjacent said escapement wheel, a piston mounted therein and a connecting rod secured to said piston and pivoted to said escapement wheel.

90 In testimony whereof I affix my signature.

GEORGE MORRISON.
